PADDING FOR IRONING BOARDS, PRESSING
MACHINE BUCKS AND ROLLS, AND THE
LIKE

Alfred M. Goodloe, Roanoke, Va., and Ralf L. Hartwell, Orange, N. J., assignors to Metal Textile Corporation, West Orange, N. J., a corporation of Delaware

Application June 1, 1937, Serial No. 145,710

2 Claims. (Cl. 38—66)

This invention relates to improvements in resiliency padding for the facing of ironing boards, pressing machine bucks and rolls, and for like purposes.

Padding for the purposes above mentioned has usually comprised layers of textile fabric or square woven metallic screening; or felted mats of vegetable or metallic fibers, hair or other filamentous material; or of mechanical or fabricated structures including helical compression springs, bristle bodies or similar arrangements. Paddings of such characters have not proven altogether satisfactory. For example, woven textile or metallic material has but little resiliency; felted material lacks uniformity of resiliency throughout its mass, and, in use, soon tends to pack down into a comparatively dense and relatively hard mass; while mechanically fabricated padding tends to easily and quickly break down in areas subjected to maximum stresses and wear, so as to soon present an uneven surface and a body lacking in uniform resiliency. None of these packings are so constructed as to snugly conform to protuberances on the goods supported thereon against smoothing or ironing pressure.

It is an object of this invention to provide a novel construction of padding for the purposes stated which is calculated to provide not only a desired degree of resiliency which is uniform throughout its mass, while at the same time providing a structure which will easily withstand, without break down, the blows or pressures to which it is normally subjected in use, but will also provide a padding of such structural characteristics as to readily yield at points to which excess pressure is applied so as to easily and snugly conform itself to protuberances in material supported thereby subject to ironing pressures, while nevertheless presenting such material smoothly spread and supported subject to the efficient application thereto or movement thereover of a pressing iron or other pressing element.

To attain the above stated object, the novel padding according to this invention is made of knitted metallic mesh material. Such material is inherently more or less springy in character, and its springiness may be enhanced by fluting, crimping or corrugating, if desired, some or all of the plies thereof forming the padding mass; and, furthermore, due to the somewhat loosely interlinked arrangement of the knitted loops forming such mesh, there is permitted a local movement or play at those portions of the area thereof which may be subjected to excess pressure, whereby the padding body will readily yield

at such areas and thus more closely and snugly conform itself to any protuberances on the material supported thereby subject to a pressing action, while nevertheless maintaining the material, as a whole, smoothly spread and sufficiently backed to assure efficient smoothing under said pressing action.

Other and more specific objects of this invention, not at this time more particularly enumerated, will be understood from the following detailed description of the same.

Some illustrative embodiments of this invention are shown in the accompanying drawings, in which:

Fig. 1 is a fragmentary plan view of a simple form of the padding material as applied to an ironing board pressing machine buck or roll or other support, as the case may be, a portion of the facing cover therefor being broken away to disclose the padding mass; Fig. 2 is a fragmentary longitudinal sectional view through the same, but drawn on an enlarged scale; Fig. 3 is a fragmentary longitudinal sectional view, similar to that of Fig. 2, but showing some of the plies of metallic mesh making up the padding body transversely corrugated to increase the elasticity or resiliency of its mass.

Fig. 4 is a fragmentary face view of a knitted metallic mesh as made of round wire, and which is utilized in the make up of the novel padding; and Fig. 5 is a similar view showing the knitted metallic mesh as made of flat or ribbon-like wire.

Fig. 6 is a fragmentary plan view of another form of padding body made up of transversely wound or folded plies of knitted metallic mesh, the facing cover therefor being broken away to disclose the padding body, and plies of the latter also being broken away to show underlying superposed plies.

Fig. 7 is a fragmentary transverse section of the padding arrangement shown in Fig. 6, but drawn on an enlarged scale.

Fig. 8 is a fragmentary sectional view of another form of padding body wherein the knitted metallic mesh is arranged in layers perpendicular to the plane of the supporting surface provided by the mass thereof.

Similar characters of reference are employed in the above described views, to indicate corresponding parts.

As shown in Figs. 1 and 2, the novel padding body 10 comprises a plurality of superposed plies of knitted metallic mesh. The knitted metallic mesh may be knitted from round wire 11 (see Fig. 4), or it may be knitted from flat or ribbon-

like wire 12 (see Fig. 5), or from wire of any other suitable or desired cross-sectional shape. Ordinarily, the wire utilized is of a character having some inherent springiness, and preferably, although not necessarily, should be of a metal resistant to corrosion, such, for example, as copper, bronze, brass, aluminum or metallic alloys having desired characteristics.

In the make up of the padding as shown in Figs. 1 and 2, a suitable number of plies of the knitted metallic mesh are overlaid one upon the other until a padding body of desired mass or thickness is obtained. Either the round or flat wire mesh may be alone employed, or combinations of both may be utilized in any desired group arrangement or in suitably alternated disposition. The padding body 10 composed of superposed plies of knitted metallic mesh is mounted on a desired support 13, which may be an ironing board, a pressing machine buck, a mangle roll, or such other foundation as is provided for the support of material to be subjected to a pressing action or operation. Over the padding body, thus mounted, is thereupon disposed and suitably secured a facing cover 14. The facing cover 14 is usually made of a suitable textile fabric, and may consist of one or more plies thereof as desired in any specific case.

The metallic mesh material may be either flat knit or tubular knit to desired ply widths, but, in either case, owing to the interlinking and crossing of the knitted loops thereof, the mesh will be somewhat corrugate or rough surfaced, so that when a plurality of plies thereof are piled one upon another, a depressibly yieldable or springy mass will result, thus providing a resilient characteristic which is uniform throughout the entire mass of the padding body.

By reason of such inherent resiliency, the padding body is very lively and quickly reacts to normal expanded condition after pressure thereupon is relaxed. As a consequence of this the padding body easily withstands the blows and pressures, to which it must of necessity be subjected in use, without tendency to break down or to become unduly compacted into a hard or uneven mass.

In addition to such uniform resilient characteristic, there is another factor which is peculiar to the knitted mesh and which increases greatly its efficiency as a padding material for the purposes stated, viz., the fact that the knitted loops thereof are somewhat loosely interlinked one with another so as to be capable of mutual give and take, interplay or relative movement, especially at local areas subjected to pressure in excess of that applied to surrounding areas. By reason of the possibility of such relative movement between the interlinked loops, stretching, expansion and contracting effects are readily permitted in the localized area subjected to excess pressure without unduly deforming or disturbing the surfaces outlying around such local areas. As a consequence of these effects, the padding body will closely and snugly conform itself to protuberances which may project from the material supported thereby subject to a pressing action or operation. For example, a button 15 projecting from the material 16 being pressed (see Fig. 2) will easily depress and sink into the padding body mass so that the latter will closely and snugly conform to the button, and in such manner as not to interfere with the smooth lying of the material surrounding the button, or the proper supporting effect upon the material of areas of the padding body outlying around the

point of impingement of said button therewith. It follows from this that smooth pressing of the material close up to the periphery of the button will be assured. In like manner, heavy seams or other projections from material being pressed will be likewise accommodated by the ready conformability of the padding material.

If it is desired to increase the elastic resiliency of a padding body made of superposed plies of knitted metallic mesh, this may be done by transversely corrugating the mesh ply. In Fig. 3, for example, the layers of the knitted mesh are shown provided with transverse corrugations 17. These corrugations are formed by bends in the legs of the knitted loops intermediate the oppositely directed loop ends of the courses of said loops. In arranging the superposed plies of thus corrugated knitted mesh, the corrugations of one ply may be staggered relatively to those of an adjacent ply so that a maximum of springy or resilient effect is obtained. When employing such corrugated knitted mesh, it is preferable to insert between the body formed thereby and the facing cover 14 a ply 18 (see Fig. 3) of uncorrugated mesh. It will be obvious that the padding body may be made up of superposed layers of corrugated and uncorrugated plies in any desired grouped or alternated relation, according to the degrees of density and of resiliency desired in the resultant padding mass.

Referring now to Figs. 6 and 7, there is shown therein a modified construction of the novel padding body. In this arrangement thereof, the padding body 19 is formed by disposing superposed strips or bands of knitted metallic mesh transversely of the longitudinal dimension of the body. The strips or bands of knitted metallic mesh may be either flat knit or tubular knit. Preferably the strips or bands are folded or wound so as to provide successive layers thereof, with those of each layer disposed side by side, that is edge to edge, and with the strips or bands of one layer superposed in staggered relation to those of an adjacent layer. This arrangement is shown in Fig. 6 more especially, wherein the strips or bands of successive layers are broken away to show of underlying layers. In said Fig. 6 the reference character 20 indicates the strips or bands of an outer layer, 21 the strips or bands of an underlying succeeding layer, 22 the strips or bands of a next succeeding layer, and 23 the strips or bands of a following underlying layer. It will be observed that the strips or bands of one layer are staggered relative to those of adjacent layers. While, as stated, such staggered relation of the strips or bands is deemed preferable, such arrangement is not absolutely essential, since if desired the strips or bands may be in register, or may be criss-crossed or disposed in other desired associated relation as may be deemed of advantage in any given case.

It will also be understood that if it be desired to increase the elastic resiliency of the padding body, thus made up of superposed layers of strips or bands of knitted metallic mesh, said strips or bands may be fluted, crimped or corrugated; and that strips or bands so treated may be combined in any desired manner with normal strips or bands.

Over the padding body made up of superposed layers of strips or bands as described is arranged a facing cover 24, such, e. g., as one or more plies of a suitable textile fabric and said padding body is mounted on a desired support 25, which may be

an ironing board, pressing machine buck, man-
5 gle roll, or the like.

In Fig. 8 is shown another modified construction
5 of padding body made up of the knitted
metallic mesh material. In this form of padding
body, the knitted metallic mesh is provided in
strips or bands, as 26, of a width corresponding
10 to the thickness of the padding body to be formed
therewith, but instead of disposing the bands
15 horizontally or parallel to the plane of the sup-
porting surface provided by the mass thereof,
the mesh material is suitably arranged in lay-
ers 27 disposed to stand edgewise or perpendic-
lar to the plane of the supporting surface pro-
15 vided by the mass thereof. The strips or bands
may be corrugated, fluted or crimped or may be
left straight as is deemed desirable in any given
case. The padding body thus formed will also
20 be found to possess a considerable degree of de-
pressive resiliency, due to the inherent springi-
ness of the metallic wire loops by which the same
is characterized. As in the other examples, when
25 the padding body of this kind is employed as a
support for material to be subjected to a pressing
action, the padding body is mounted on a suitable
base 28 and its outer surface is covered by a
suitable facing cover 29.

While the novel padding material as above de-
scribed is adapted for use as a support for ma-
30 terial to be subjected to a pressing action or op-
eration, it will be understood that the same is
also adapted for various other uses. For example,
the padding is well adapted for use in furniture
35 and like upholstery work, and for other purposes
in connection with which a conformable and uni-
formly resilient padding material is desired.

It will be obvious that many changes or varia-
tions could be made with respect to the novel

padding material above described, and many ap-
parently different embodiments of this inven-
tion could be made without departing from the
scope thereof as defined in the following claims.
It is therefore intended that all matter contained
in the above description or shown in the accom-
panying drawings shall be interpreted as illus-
trative and not in a limiting sense. 5

We claim:

1. A padding body formed from knitted metallic 10
mesh comprising superimposed layers of knitted
bands, the bands of each layer being laid sub-
stantially transverse to the length of the body
and arranged edge to edge, the bands of adjacent
15 layers being disposed in relative staggered rela-
tion, and the bands of at least some of said lay-
ers having corrugations transversely traversing
the same, said corrugations being formed by
bends in the legs of the knitted loops intermediate
20 the oppositely directed loop ends of the courses
of said loops.

2. A resilient pressure sustaining pad comprising,
a suitable base, a padding body supported by
said base, said padding body being formed from
metallic mesh comprising superimposed layers of 25
knitted bands, the bands of each layer being laid
substantially transverse to the length of the body
and arranged edge to edge, the bands of adjacent
layers being disposed in relative staggered rela-
tion, the bands of at least some of said layers 30
having corrugations transversely traversing the
same, said corrugations being formed by bends
in the legs of the knitted loops intermediate the
oppositely directed loop ends of the courses of
35 said loops, and a facing of flexible material cov-
ering said padding body. 35
